Primary Examiner—Louis S. ZarfesAssistant Examiner—Monica A. HannonAttorney, Agent, or Firm—Steinberg, Raskin & Davidson[57] CLAIM

The ornamental design for a merry-go-round make-up case, as shown and described.

DESCRIPTION

FIG. 1 is a perspective view of a merry-go-round make-up case in its closed position showing my new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof; and,

FIG. 8 is a perspective view of a make-up case, in its opened position showing my new design.
